Specification for Design.

Patented Aug. 21, 1917.

Application filed March 20, 1916. Serial No. 85,529. Term of patent 14 years.

To all whom it may concern:

Be it known that I, ARTHUR T. HOPKINS, a citizen of the United States, residing at Cleveland, county of Cuyahoga, and State of Ohio, have invented a new, original, and ornamental Design for Playing-Balls, of which the following is a specification, reference being had to the accompanying drawing, forming part thereof, wherein—

The figure is a view of a playing ball showing my new design.

My invention comprises a playing ball having elongated depressions arranged substantially as shown.

I claim:

The ornamental design for a playing ball as shown and described.

Signed at Cleveland, Ohio, this 16th day of March, 1916.

ARTHUR T. HOPKINS.
